UNITED STATES PATENT OFFICE.

CORNELIUS HOOD, OF BENTON HARBOR, MICHIGAN.

STEP-LADDER.

SPECIFICATION forming part of Letters Patent No. 554,695, dated February 18, 1896.

Application filed October 12, 1895. Serial No. 565,473. (No model.)

To all whom it may concern:

Be it known that I, CORNELIUS HOOD, a citizen of the United States, residing at Benton Harbor, in the county of Berrien and State 5 of Michigan, have invented certain new and useful Improvements in Step - Ladders, of which the following is a full, clear, and exact description, reference being had to the accompanying drawings, forming a part of this 10 specification.

My invention relates generally to step-ladders and particularly to certain improvements connected with the rear or brace portion.

The main object of my invention is to construct a step-ladder which can be firmly supported upon an uneven or inclined surface, and a further object is to provide a brace for the ladder when so supported.

Another object is to provide an improved 20 form of hinge-brace between the front and rear portions or members of the ladder, whereby a stronger joint is secured, one that will readily lock itself when the sections are spread apart and one that will readily fold when the 25 sections are folded together.

A still further object is to provide an improved construction of shelf for supporting buckets and the like near the top of the ladder.

The foregoing and such other objects as 30 may occur from the ensuing description are attained by the device illustrated in the accompanying drawings, in which—

Figure 1 is a perspective view of the ladder 35 embodying the adjustable leg feature of my invention, the shelf being omitted. Fig. 2 is a side view illustrating the adjustable leg in a raised position. Fig. 3 is a central longitudinal section. Fig. 4 is a transverse section on the line 4-4, Fig. 3. Fig. 5 is a bottom plan view of the shelf. Fig. 6 is a section on line 6-6 of Fig. 5. Fig. 7 is a detail view of the connection between the fixed and adjustable leg.

In the practical application of my invention I construct a step-ladder with the front or step portion, A, the rear or brace portion, B, and the top shelf or platform C, said rear portion being hinged at c to either the platform or front section, as desired, and these parts may be of the usual or any approved construction.

In order to properly hold the rear portion, B, in open position, I provide a hinge-brace D, comprising the rods or bars d d', connected 55 to the side members of the front and rear portions respectively and connected at their inner ends by means of cross-strips d² d³, respectively, said strips being hinged together upon their lower edges by a hinge d⁴, so that 60 said brace will break and fold upwardly as the front and rear portions are folded together. When the sections are spread apart, as shown in Fig. 1, the hinged brace will be folded out flat, the flat edges of the strips 65 contacting and thus making a secure brace between the front and rear sections.

For the purpose of supporting the ladder upon inclined or uneven surfaces, I provide 70 adjustable legs E, which are attached to the outer faces of either the front section, A, or the rear section, B, or both sections, as may be desired, through the medium of a block F, box or loop F', and set-screw F², the block and box being vertically slidable upon the 75 section B, and the legs are connected to said blocks by hinge-joints G, so that, in addition to the legs being vertically slidable, they are also laterally movable, so they can be spread out to form a wider base and thus brace the 80 ladder when resting upon inclined or uneven surfaces.

A pivoted brace-link H connects the section B and legs E at each side and prevents the legs spreading too far outward.

It will thus be perceived that I provide a 85 novel form of brace between the front and rear portions of the ladder, and also that adjustable and laterally-movable adjustable legs are provided, thus constituting an exceedingly simple, durable and convenient form of 90 step-ladder. It is also desired to employ an improved form of shelf K, which shelf is supported upon a U-shaped bail L, secured at its upper ends to the top of the rear portion or 95 member, B, and if preferred the said bail may be used as the pivotal connection between the front and rear sections of the ladder.

The shelf K is flared at the forward end and provided with a cleat k of similar shape, 100 said end fitting into a dovetailed recess k² in the bottom of the top step, the purpose of such construction being to prevent the tilting or swinging of the shelf, as the peculiar shape

of the end fitting in the aforesaid recess successfully prevents this.

It will be understood that I may use all the features set forth in constructing my ladder, 5 or I may use any one or more of them, as desired, all being comprehended in my invention. It will also be evident that the dovetailed construction and arrangement may be altered somewhat without departing from the 10 broad principles of my invention, which involves a step-ladder constructed to be supported and braced upon uneven surfaces, the central hinge-brace and locking shelf.

Having thus described my invention, what 15 I desire to claim and secure in my Letters Patent is—

1. In a step-ladder, the front and rear sections or members, connected as usual, and the vertically-slidable and laterally-adjustable legs connected to the sides of said ladder, substantially as shown and described.
2. In a step-ladder, the front and rear sections or members connected as usual, the vertically-slidable and laterally-adjustable legs, 25 and means for connecting the same with the rear section or member, substantially as shown and described.
3. In a step-ladder, the front and rear sections connected as usual, the slidable blocks, 30 box and set-screw, and the legs attached to said blocks, and adapted to be moved both vertically and laterally, substantially as shown and described.
4. In a step-ladder, the front and rear sec-

tions, the slidable blocks, boxes and set-screws, the legs hinged to the blocks, and the brace-links connecting the legs and rear section, substantially as shown and described.

5. In a step-ladder, the front and rear sections, and a central hinge-brace comprising 40 the transverse strips, connecting-hinge and rods connecting the strips and ladder, substantially as shown and described.

6. In a step-ladder, the front and rear sections, the rods connected therewith, the strips 45 connected to the rods, and the hinges connecting said strips, substantially as shown and described.

7. In a step-ladder, the combination of the front and rear sections, the depending bail, 50 and a shelf supported by said bail and having its forward end secured in a dovetailed recess in the bottom of a step on the front section, substantially as described.

8. In a step-ladder, the combination of the 55 front and rear sections, a step on the front section provided with a dovetailed recess in the bottom thereof, a depending bail and a shelf supported by said bail and provided with a flared forward end and a cleat secured 60 thereto and adapted to be fitted into said recess in the step, substantially as and for the purpose described.

CORNELIUS HOOD.
